[57] CLAIM

The ornamental design for a hand-held computer, as shown and described.

DESCRIPTION

FIG. 1 is a perspective view of my new design for a hand-held computer;

FIG. 2 is a top plan view;

FIG. 3 is a front elevational view;

FIG. 4 is a rear elevational view;

FIG. 5 is a rear elevational view of an alternate embodiment wherein the only difference resides in the showing of dust/splash covers over the connection ports;

FIG. 6 is a left side elevational view of FIG. 1;

FIG. 7 is a right side elevational view; and,

FIG. 8 is a bottom plan view.
